UNITED STATES PATENT OFFICE.

CHARLES DE LUKACSEVICS, OF NEW YORK, N. Y., ASSIGNOR TO JULIUS WINTER, OF NEW YORK, N. Y.

CARBURETER.

1,337,051.

Specification of Letters Patent. Patented Apr. 13, 1920.

Application filed December 29, 1917. Serial No. 209,570.

To all whom it may concern:

Be it known that I, CHARLES DE LUKACSEVICS, a citizen of the United States, residing at New York, in the county of New York and State of New York, have invented new and useful Improvements in Carbureters, of which the following is a specification.

This invention relates to improvements in carbureters for internal combustion engines, proposing a carbureter of the type disclosed in my Letters Patent, No. 1,257,195, granted February 19, 1918, wherein the construction is such that certain parts may be made of bakelite and so arranged or organized that bakelite surfaces alone are exposed to the fuel mixture, with resultant advantages as set forth in my said patent.

The present carbureter retains all the salient features of structure and advantage of the particular carbureter disclosed in my said patent; and the invention consists in certain detail features of improvement whose objects are to facilitate manufacture, to enable the substantial control of the quantity of hydrocarbon fuel delivered from the nozzle, and to provide for the correct proportioning of the constituents of the mixture by correlation of the operations of the respective air and fuel controlling means.

The features of structure, combination and relation which constitute the invention will be set forth in detail as the description proceeds.

An embodiment of the invention is illustrated in the accompanying drawings, wherein:

Figure 1 is a vertical, central, sectional view of a carbureter in which the features of the invention are incorporated, the interior of the carbureter being fully opened for the admission of the air and hydrocarbon fuel.

Fig. 2 is a cross-sectional view on the line 2—2 of Fig. 1 but showing the parts in position to occlude the air and liquid fuel.

Fig. 3 is an enlarged detail sectional view of the tube which provides the fuel nozzle and certain parts appurtenant thereto.

Fig. 4 is a detail view of a part in association with said tube to provide the fuel jet orifices.

Similar characters of reference designate corresponding parts throughout the several views.

The features of the invention will be best understood if their description be prefaced by a description of those structural features which the carbureter disclosed herein has in common with the carbureter shown in my 60 said patent.

The casing of the carbureter is preferably made of bakelite and provides a carbureting chamber 1 to which fuel is delivered from a fuel nozzle 2 and air is delivered from an air supply pipe 3, the latter being preferably molded with the casing. The float feed chamber 7 is preferably molded integrally with the bakelite body part 39 of the carbureter casing. The casing includes 65 an upper part which is provided with the attachment flange 34 and which, in the embodiment shown, has a lateral extension 47 upon which said attachment flange is arranged.

The cylindrical body part 39 of the carbureter casing incloses the operating parts which include the regulating valve 10, the valve element 19, and the air valve guide 11. The supply pipe 6 for the nozzle 2 leads 70 from the float feed chamber 7 and is formed in the carbureter base.

The float feed chamber is provided with a suitable float feed mechanism 8 and has a cover plate 7^a of bakelite which is held 75 closed by a spring 40 secured to the carbureter casing.

The valve guide 11, which is preferably of metal, depends internally from the upper end of the body 39, its upper edge portion 90 preferably being clamped between the upper edge of said body and the adjacent edge of the upper member of the carbureter casing. The regulating valve 10 is preferably formed of bakelite and is of tubular or 95 cylindrical form, having a close sliding fit within the valve guide 11. For the purpose of regulating the volume of the mixture delivered to the chamber 1 the valve 10 co-operates at its upper end with the valve element 106 100 which is likewise preferably made of bakelite. For the purpose of regulating the velocity of the air, provision is made for a variable throatway 17 in concentric external relation to the discharge end of the nozzle 2, 105 and for the provision of the said throatway the valve 10 has a Venturi-type cross-section.

The valve 10 also serves the function of a main air control valve and accordingly has its lower portion interrupted to provide open 110

spaces 27 which function as air inlet openings and are controlled by the guide 11; and below said opening the valve 10 is formed with a normally closed base whereby air 6 from the inlet 3 can normally flow into the interior of the valve 10 only through the openings 27 whose efficient size is regulated by the elevation at which the valve 10 is held. In connection with its control of the 10 air admitted by the inlet 3, the valve 10 has incorporated therewith, and as part of its normally closed base, a compensating valve 42 which has a close sliding fit on the nozzle tube 2^a and is normally seated against 15 a flanged ring 43 by a helical spring 44. The spring 44 surrounds the tube 2^a and bears at its upper end against retaining fingers 45 carried by the valve 10. The valve 42 normally closes the lower end of 20 the valve 10 with which it is movable as a unit. Its object is to provide for an additional air supply in the comparatively infrequent cases when the normal maximum amount of air admitted to the carburetor in 25 the lowermost position of the valve 10 is insufficient; and in the accomplishment of this object the valve 42 is lifted from its seat, as shown in Fig. 1, against the pressure of the spring 44 by the engine suction. 30 The fingers 45 which are anchored in the valve 10, the ring 43 and the valve 42 are preferably of metal.

The foregoing features of structure and operation are common to the carburetor 35 herein disclosed and the carburetor which is disclosed in my said patent and the features of the present invention, to which the following description will be directed may be regarded as imposed upon and as having 40 their utility in connection with the features of structure and operation above described.

The main element of the fuel nozzle is an upright tube 2^a, preferably of metal, which is anchored in the base of the carburetor 45 casing, having a drain cock 2^b at its lower end, and which is also utilized in securing together the parts of said casing, for this purpose being employed in co-operation with a stem 35. The stem 35 is pendent from 50 the upper member of the carburetor casing and carries at its upper end an externally located nut 37 while its lower end is threaded, as at 38, for some distance to screw into the tube 2^a. Upon the removal of the nut 55 37, the parts of the carburetor casing may be separated, thereby enabling easy access to the inclosed working parts.

The stationary valve element 19 is mounted upon the stem 35 and is preferably suitably secured to a bushing 46 which is anchored in the upper member of the carburetor casing. The valve element 19 has in 60 its lower portion a recess 50 formed as an enlargement of the central opening through 65 which the stem 35 projects, said recess serv-

ing as a housing for certain parts to be hereafter referred to.

In order to provide for the flow of fuel beyond the upper end of the tube 2^a, that portion of the stem 35 which is screwed into 70 said tube is formed with a suitable number of fuel ducts 51 which extend from the lower end of the threaded portion to points adjacent the upper end of the tube 2^a. The said tube is preferably formed adjacent its 75 upper end with a suitable well 52 in which is arranged absorbent material. The discharge end of the tube 2^a is above the normal fuel level and the absorbent material in the well 52 acts with capillary effect to conduct 80 the fuel from the ducts 51 to the discharge end of the tube 2^a.

The discharge end of the tube 2^a is preferably internally tapered and is in co-operation with a nozzle sleeve 53 which surrounds 85 the stem 35 above said tube. The lower end of the sleeve 53 is fashioned to conform to the discharge end of the tube 2^a and has a nested fit in said discharge end. To provide for the jet delivery of fuel the sleeve 53 has 90 its under-face which adjoins the discharge end of the tube 2^a formed with any desired number of radial nozzle ducts 54 which may be of any desired width or depth. The ducts 54 will have their number and proportions 95 selected with regard to the particular engine with which the carburetor is to be used. The sleeve 53 is held in operative relation to the tube 2^a by an expansion spring 55 which surrounds the stem 35 and is arranged within the recess 50, bearing at its 100 upper end against a shoulder 56 formed internally of the valve element 19.

For the regulation of the amount of fuel delivered, by means of the ducts 54, from 105 the tube 2^a there is provided a fuel regulating sleeve 57 which incloses the nozzle sleeve 53 and has a close sliding fit thereon and on the tube 2^a. The sleeve 57 is partly housed in the recess 50 of the valve element 19 and 110 has a portion which projects some distance below said recess and which is connected to the valve 10 in such manner that said regulating sleeve will participate in all the movements of said valve. For the connection of 115 the valve 10 and the regulating sleeve 57 the fingers 45 are preferably utilized and, as shown, are provided with inwardly directed terminal pins 58 which are fitted into openings formed in said regulating sleeve. 120

In the embodiment shown, the sleeve 57 is provided with a series of vertical slots 59 whose number and arrangement accords with the ducts 54 of the nozzle sleeve 53 and which control the respective ducts. In order to effect, automatically, the proper proportioning of the constituents of the mixture under all conditions of engine speed the slots 59 are of graduated length whereby as the valve 10 is lowered to admit more 125

air the number of ducts 54 effective to discharge fuel will be increased and the amount of fuel discharged will be proportionately increased and as the valve 10 is raised to 5 decrease the amount of air admitted the number of ducts 54 effective to discharge fuel and, therefore, the amount of fuel discharged will be similarly and proportionately decreased. The graduated relation of 10 the slots 59 is clearly shown in Fig. 1 from which it will be noted that the lower ends of the slots are at progressively lower elevations; and the efficacy of the slots 59 for the purpose stated is due to the fact that in 15 any elevated position of the sleeve 57 certain of the slots will be located above the corresponding ducts 54 and the said ducts will, therefore, be occluded from the interior of the carburetor, the number of ducts thus occluded being obviously greater as the sleeve 20 57 is raised and less as said sleeve is lowered.

As in my above mentioned patent the valve 10 is under manual control but the 25 present invention introduces an improved device for effecting the upward and downward movements of said valve. For the operation of the valve 10 a rock-shaft 60 extends across the lower portion of the carburetor casing, having its bearings in the 30 walls of said casing, and is provided with a pair of arms 61 whose inner faces are formed with confronting grooves 62, and there is slidably mounted on the tube 2^a a 35 collar 63 which is connected by straps 64 to the ring 43 (the said ring being an element of the base of the valve 10) and is provided with laterally projecting pins 65 which work in the grooves 62 and may be 40 fitted with anti-friction rollers. In order that the arms 61 may be operated by the shaft 60 and may also be susceptible of angular adjustment with reference to said shaft, to enable their adaptation in carburetor casings of varying proportions, said arms are carried by a sleeve 66 which is 45 fitted on the shaft 60, said sleeve and said shaft having throughout their circumference inter-matching corrugations by which 50 the sleeve is made fast to the shaft in any position to secure a desired angular relation of the arms 61. The shaft 60 is provided externally of the casing with an operating crank 16 which may be linked or otherwise 55 suitably connected to an operating lever (not shown). The valve 10, carrying with it the sleeve 57, is positively raised and lowered by respective upward and downward 60 movements of the arms 61. In such movements of said arms the pins 65 obviously have a sliding action in the slots 62. The pins 65 are located opposite to one another, one at each side of the axial center of the valve 10 and the operating thrust which is 65 applied to said pins by the arms 61 is, there-

fore, effective to produce easy and regular sliding movements of the valve 10 in which any binding tendency is entirely eliminated.

The operation will be readily apparent from the foregoing description. Obviously, 70 as the valve 10 is raised, the space between it and the valve element 19 is diminished and as the valve 10 is lowered, such space is increased. With the decrease of the area of communication between the internal space 75 delimited by the valve 10 and the chamber 1, there is, of course, a decrease of suction influence in such internal space, but this does not interfere with the supply of fuel necessary for low speed running, since the 80 low inductive value of the suction influence is compensated by the increase in the velocity of the air which moves in stream-like formation past the discharge end of the nozzle and which takes up the gasoline 85 vapor or finely-divided gasoline at a period when its velocity is greatest, or nearly so. The connection of the valve 10 with the fuel regulating sleeve 57 whereby said sleeve participates in the movements of said 90 valve and is effective to increase the amount of the fuel delivered by the nozzle as the valve 10 is moved to increase the amount of air and to decrease the amount of fuel as the valve 10 is moved to decrease the amount 95 of air, positively insures the correct proportioning of the mixture in connection with the regulation of its quantity by the valve 10.

Having fully described my invention, I 100

claim—

1. In a carburetor, in combination, a casing having an air inlet, an upright nozzle located centrally within said casing and discharging above said air inlet, said nozzle having a plurality of radial discharge ducts, 105 a tubular regulating valve surrounding said nozzle and mounted for up and down sliding movement, means in coöperation with said valve in its movements for controlling the admission of air, a fuel regulating sleeve 110 surrounding said nozzle and having slots controlling the respective discharge ducts and of graduated length, connections between said regulating valve and said regulating sleeve whereby the latter participates in 115 the movements of the former, a carbureting chamber above said nozzle, and a stationary valve element between said carbureting chamber and said nozzle with which the valve coöperates at its upper end, said valve 120 element having a central recess into which said regulating sleeve projects.

2. In a carburetor, in combination, a casing having an air inlet, an upright nozzle located centrally within said casing and discharging above said air inlet, said nozzle having discharge ducts, a tubular regulating valve surrounding said nozzle and mounted for up and down sliding movement, means 125 in coöperation with said valve in its move- 130

- ments for controlling the admission of air, a fuel regulating sleeve surrounding said nozzle and mounted for up and down sliding movement, said sleeve being constructed 5 whereby, when raised, it decreases the amount of fuel delivered by the nozzle and, when lowered, it increases the amount of fuel so delivered, connections between said regulating valve and said regulating sleeve 10 whereby the latter participates in the movements of the former, a carbureting chamber above said nozzle and a stationary valve element between said carbureting chamber and said nozzle with which the valve coöperates 15 at its upper end, said valve element having a central recess into which said regulating sleeve projects.
3. In a carbureter, in combination, a casing including a body part and an upper member, an upright nozzle tube mounted within the body part, a stem pendent from the upper member and threaded within the nozzle tube, said stem having grooves in its threaded portion whereby the fuel may pass 20 to the upper end of the nozzle tube, and a nozzle sleeve fitted upon said stem and co-operating with the upper end of said nozzle tube, said nozzle sleeve having fuel discharge ducts.
4. In a carbureter, in combination, a casing having an air inlet, an upright nozzle tube mounted within said casing, a tubular regulating valve surrounding said nozzle, a carbureting chamber above said nozzle, a stationary valve element between said carbureting chamber and said nozzle with which the valve coöperates at its upper end, said valve element having a recess and a nozzle sleeve mounted within said recess for coöperation with said nozzle tube, said nozzle sleeve having fuel discharge ducts.
5. In a carbureter, in combination, a casing having a body part and an upper part, an upright nozzle tube mounted in the body 45 part, a stem pendent from the upper part and threaded in said nozzle tube, a nozzle sleeve mounted upon said stem for coöperation with the nozzle tube, a spring pressing said sleeve against the upper end of the nozzle tube, a tubular regulating valve surrounding the nozzle tube, a carbureting chamber located above the nozzle tube, and a stationary valve element between said carbureting chamber and the nozzle tube with 50 which the valve coöperates at its upper end, said valve element having a recess in which the nozzle sleeve and its spring are arranged.
6. In a carbureter, in combination, a casing having an air inlet, an upright nozzle located centrally within said casing and discharging above said air inlet, said nozzle 55 having discharge ducts, a tubular regulating valve surrounding said nozzle and mounted for up and down sliding movement, said tubular regulating valve having a normally closed base, a compensating air valve which forms a part of the normally closed base of the regulating valve, a fuel regulating sleeve surrounding the nozzle 60 and mounted for up and down sliding movement, said sleeve being constructed to regulate the amount of fuel delivered by the nozzle, a plurality of arms projecting from the regulating valve and fitted to the regulating sleeve, thereby to cause said sleeve to participate in the movements of the valve, and a spring bearing between said arms and the compensating valve to hold the latter 65 normally closed.
7. In a carbureter, in combination, a casing having an air inlet, an upright nozzle tube located centrally within said casing and discharging above said air inlet, a tubular regulating valve surrounding said nozzle 70 and mounted for up and down sliding movement, and means for moving said valve, comprising a rock-shaft fitted in the lower part of said casing, a collar slidably fitted on said nozzle tube and connected to said regulating valve, a pair of arms projecting from said rock-shaft and having grooves in their confronting faces, and pins carried by said collar and working in the grooves of 75 said arms.
8. In a carbureter, in combination, a casing having an air inlet, an upright nozzle tube located centrally within said casing and discharging above said air inlet, a tubular regulating valve surrounding said nozzle tube and mounted for up and down sliding movement, and means for moving said valve, comprising a rock-shaft fitted in the lower part of said casing, a collar 80 slidably fitted on said nozzle tube and connected to said regulating valve, a pair of arms projecting from said rock-shaft and having grooves in their confronting faces, pins carried by said collar and working in the grooves of 85 said arms, and a sleeve carrying said arms and fitted on said rock-shaft, said sleeve and said rock-shaft having intermeshing corrugations whereby said sleeve may be positioned on said rock-shaft to secure any desired angular relation 90 of said arms.
- In testimony whereof I have hereunto set my hand in presence of two subscribing witnesses.
